UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

THREAD-CONTROLLING MECHANISM FOR OVERSEAMING-MACHINES.

1,232,381.

Specification of Letters Patent.

Patented July 3, 1917.

Application filed September 15, 1913. Serial No. 789,835.

To all whom it may concern:

Be it known that I, LANSING ONDERDONK, a citizen of the United States, residing at New York, in the county of New York, State 5 of New York, have invented certain new and useful Improvements in Thread-Controlling Mechanism for Overseaming-Machines, of which the following is a description, reference being had to the accompanying drawing and to the figures of reference marked thereon.

The invention relates to new and useful improvements in thread controlling mechanisms for over-seaming machines, and more 15 particularly to the thread controlling mechanism for the needle thread and the under thread carrying looper.

An object of the invention is to provide means for controlling the needle thread in 20 an over-seaming machine so that the needle loops may be drawn to a predetermined position, regardless of varying thicknesses in the material, so as to form an over-seaming stitch wherein the purl is uniformly laid.

25 A further object of the invention is to provide an over-seaming machine with a thread controlling mechanism for the under thread carrying looper which operates upon the thread of this looper to take up the 30 thread in proper timed relation to the forming of the stitch, also to pull thread from the supply for this thread carrying looper.

A still further object of the invention is to provide an over-seaming machine having 35 a thread carrying needle, an under thread carrying looper and an over edge thread carrying looper, wherein the thread for each of the stitching implements is separately controlled so that a uniform over edge stitch 40 may be produced.

These and other objects will in part be obvious, and will in part be hereinafter more fully described.

In the drawings, which show by way of 45 illustration, one embodiment of the invention,

Figure 1 is a front elevation of a sewing machine embodying my improvements, certain of the parts being broken away and 50 shown in section, and also certain of the parts omitted in order to more clearly show the stitch forming elements and the controlling devices therefor;

Fig. 2 is a similar view on an enlarged 55 scale, showing the thread carrying loops

and the controlling devices for the threads of these loopers, said loopers being in a different position from that shown in Fig. 1;

Fig. 3 is a view similar to Fig. 2, with the thread carrying implements positioned 60 as in Fig. 1;

Fig. 4 is a view similar to Fig. 1 on an enlarged scale, showing the forward end of the machine only and the thread carrying 65 loopers positioned as in Fig. 2;

Fig. 5 is a diagrammatic view showing the position of the loops in the various threads in one form of stitch made by my improved machine;

Fig. 6 is a detail showing the thread eye 70 or loop of the auxiliary pull-off;

Fig. 7 is a detail showing the main pull-off in its extreme raised position.

The invention consists generally in providing an over-seaming machine having a 75 needle, an under thread carrying looper and an over edge thread carrying looper with controlling devices for the needle thread,

which operate to position the needle loops in a predetermined relation to the edge of 80 the fabric, which controlling mechanism is so constructed that when once adjusted for

positioning the needle loops, they will remain in this predetermined position relative to the edge of the fabric, even though the 85 thickness of the fabric varies. In other words, when the fabric increases in thickness

a greater amount of thread is furnished to the needle so as to supply the precise increase demanded to still maintain the same 90 position of the needle loops relative to the edge of the fabric. The invention consists further in providing a controlling mechanism for the under thread carrying looper,

which operates in timing with the looper 95 so that the slack thread formed by the movements of the looper may be taken care of, and when the looper dwells, this thread controlling device therefor also dwells. Said

thread controlling device is also so constructed as to pull back the thread through 100 the eye of the looper and set the stitch and thus position the looper thread so that the point of the looper is free to enter the needle loop when said looper advances. This

thread controlling device for the under thread carrying looper also takes up any slack in the looper thread at the extreme 105 forward movement of said looper and gives up slack thereto so as to permit the over

110

edge carrying looper to be readily withdrawn from the loop of thread formed by this lower thread carrying looper without straining or chafing the same.

Referring more in detail to the drawings, my improved machine consists of a bed plate 1, from which rises a standard 2, having an overhanging arm 3. A needle bar 4 is mounted to reciprocate in the forward end 10 of the overhanging arm and carries a needle 5. The needle bar is reciprocated by a lever 6, which is connected by a link 7 to the needle bar. The needle lever 6 is oscillated on its fulcrum 8 by a link 8^a, which coöperates with an eccentric on the main shaft 10. Said needle carries a thread *a*, which is led from the supply through a suitable guide 11 to a tension 12, and thence to a pull-off 13. This pull-off consists of three 15 spaced fixed thread guides 14, and movable guides 15 operating between the respective fixed thread guides 14. The movable thread guides are carried by a bracket 16 fastened at 17 to the needle lever. The fixed guides 20 14 are also carried by a bracket which is adjustably secured to the overhanging arm by a screw 18. The needle thread *a* is led from the pull-off 13 to an auxiliary pull-off and slack thread controller, which consists 25 of thread guides 19, which are spaced from each other and carried by an arm 20 pivoted at 21 to the overhanging arm, and having a segment gear 22 which meshes with a rack bar 23 fixed to the presser foot bar 24. This 30 presser foot bar carries the usual presser foot 25 and is held yieldingly against the fabric which in turn holds the same on the work support and coöperates with the feed dog in feeding the material. This auxiliary 35 pull-off and thread controller also includes a thread guiding eye or loop 26, which is fixed at 27 to the needle lever, and said thread eye or loop engages the needle thread between the thread guides 19. The needle 40 thread *a*, after leaving the auxiliary pull-off and slack thread controller, passes through a stationary thread guide 28, and thence to an auxiliary tension 29 and finally to the eye of the needle. 45 Coöperating with the needle beneath the work support is a thread carrying looper 30 which is provided with a looper thread *b*. By a thread carrying looper throughout the description and claims, I refer to a 50 looper having thread eyes through which a looper thread passes in contradistinction to a looper having a hook merely engaging the thread and carrying the same. This thread carrying looper 30 is pivoted to 55 swing on a support 32 and is moved back and forth by a link 33, which is pivoted at one end to the looper and at the other end to a rock arm 34. The rock arm 34 is pivoted at 35 to the standard and is connected by 60 a link 36 to the needle lever extension 37.

The link 36, when the looper is at the forward end of its stroke, is substantially in line with the needle lever extension 37, as clearly shown in Fig. 2 of the drawing, and, therefore, the looper will be given a 70 dwell at the forward end of its stroke. This looper operating mechanism, however, forms no part of the present invention.

Also coöperating with the needle and with the lower thread carrying looper 30 is 75 a third thread carrying looper 38, having a looper thread *c*. This looper is mounted on an arm 39 fixed to a shaft 40, which, in turn, is rocked by a link 41, operated by a crank arm on the forward end of the main 80 shaft 10.

In the operation of the devices as above described, the needle passes through the fabric and raises slightly to throw out the loop which is controlled by the looper 30, 85 which moves forward to the position shown in Figs. 2 and 4. The over edge thread carrying looper 38 moves between the looper thread *b* and the body of the looper, that is, into the loop formed by this looper 90 30, and also moves to a position above the work support so that the needle on its next descent will pass between the looper thread *c* carried by the looper 38 and the body of the looper 38,—that is, into the loop of 95 thread formed by this looper 38.

In Fig. 5 of the drawing I have shown diagrammatically an over edge stitch encircling the edge of two layers of fabric F. In this view *a* indicates the loops formed by the needle thread, *b* the loops formed by the looper 30, and *c* the loops formed by the looper 38. In this form of stitch, it is desirable that the needle thread loop shall extend through the fabric and then be drawn to the edge of the fabric and maintained in this predetermined position relative to the edge of the fabric, regardless of any varying conditions in the thickness of the fabric, during the crossing of seams or the like. 105

The above described mechanism for controlling the needle thread accomplishes this uniform laying of the needle loops relative to the edge of the fabric. Starting out, the needle is in its raised position, and the thread eye or loop 26 is in its raised position. As the needle moves down, slack thread will be given to the needle. The main pull-off is at this time slightly above the needle thread and ineffective to take up the needle thread 110 or pull thread from the supply. As the needle starts downward, it moves between the body of the looper 38 and the thread carried thereby. The needle thread leads from the eye of the needle to the previous 115 stitch, or interlocking of the loops, and, therefore, the needle loop will be led over the looper thread *c*, as shown in Fig. 2, and should at this time be slack. It is slack, as above noted. A further downward move- 120 125 130

ment of the needle causes the point thereof to enter the fabric, and the forming of the needle loop in the fabric takes up the slack in the needle thread, and the looper 38 is at this time retracted, permitting the thread *c* running in the eye of the looper 38 to the previous interlocking of the loops, to be drawn down onto the fabric. The main pull-off now comes into action, while the 10 needle is moving down, and pulls thread from the supply, through a tension, for the needle on the next stitch. This main pull-off takes no part in the setting of the stitch, except that it holds the thread taut so that 15 the needle as it finishes the lower end of its stroke, will draw the loops to assist in setting the stitch.

On the first upward movement of the needle, the main pull-off gives slack to the 20 needle thread, so that it is entirely slack, and this assists the needle in throwing out its loop for the entrance of the looper 30. The continued upward movement of the needle lever causes the thread loop or eye 26 to engage the needle loop and take up the slack thread given up by the main pull-off, but it also continues the movement after the main pull-off becomes idle and pulls a measured amount of thread through the tension 25 from the supply. The amount of thread pulled through the supply depends upon the distance this thread eye or thread loop moves above the thread guides 19. As above described, the thread guides 19 are carried by an arm 30, the position of which is determined by 35 the presser foot. If the thickness of the fabric increases for any reason, the presser foot is raised. This lowers the arm 20 and the thread guides 19 so that more thread will 40 be pulled off, and, on the other hand, when the presser foot is returned to normal position, the arm 20 will be raised and a less amount of thread pulled off. I have, therefore, provided in connection with a three-thread overseaming machine a needle thread 45 controlling mechanism which pulls off and supplies a measured amount of thread for the needle so that the needle loops may be carried to one side of the line of stitching as 50 defined by the needle punctures and maintained in a predetermined position relative to the edge of the fabric throughout the entire seam.

While I have described my improved 55 needle thread controlling mechanism as especially adapted for a three-thread overseaming machine, it will be understood, however, that from certain aspects of the invention, it may be used in connection with other 60 complementary thread carrying implements, or a single thread carrying implement, and in any stitch forming mechanism wherein it is desired to carry the needle loop to one side of the line of stitching as defined by the 65 needle punctures, and maintain the needle

loops in a predetermined position relative to the edge of the fabric.

The above description sets forth in detail the construction and the mode of operation of the controlling devices for the needle thread. It is well understood that in the sewing machine art in order to make a stitch of uniform character, the threads of the devices coöperating with the needle must also be properly controlled. The thread controlling mechanism for the looper thread *b*, that is, the thread carried by the looper 30, consists of the following elements:

This thread *b* is led from the supply through a thread eye 42 carried by the needle lever extension, and as this thread eye moves back and forth with the needle lever extension, the thread will be positively pulled from the supply. From the thread eye 42 this looper thread passes through a guide 43 and thence a tension 44. From the tension 44 the thread is led through an eye or guide at the outer end of a movable arm 45, which coöperates with a fixed thread guide 46. From the fixed thread guide 46 the thread passes to a second fixed thread guide 47, shown in dotted lines in Fig. 2, and carried by an arm 48 fixed to the bed plate of the machine. From this thread guide 47 the thread leads directly to the 95 thread eyes in the looper.

The movable arm 45 is fastened to the rock arm 34 which moves the looper 30 into and out of the needle loop. The arm 45 is rigidly attached thereto and moves with this rocker. Said arm moves from a position above the thread guide 46, as shown in Fig. 1, to a position slightly below the same, as shown in Fig. 2. Inasmuch as this movable thread guide is carried by and fixed to the 100 rocker, which moves the looper, it will be apparent that said arm only moves when the looper is moving, and dwells when the looper dwells, as above described. This thread carrying looper moves into the needle loop and to the full forward end of its stroke where it dwells so as to permit the over-edge looper to move between the looper thread carried by the looper 30 and the body thereof. It is desirable that this looper 110 shall have a relatively short stroke, otherwise a very large needle loop will be pulled, and this would have to be taken up in the setting of the stitch. It is, therefore, essential to provide means for giving this looper 120 an extended dwell at the forward end of its stroke. If the thread controller should continue to move after the looper stops and during this dwell, then the looper thread of this looper would be taken up, which might 125 result in the breaking of the thread. It is very essential that this thread controlling arm of the looper thread *b* should move in the same timing as the looper. The thread guide 46 is carried by a rod 49, which is ad-

justably mounted in a bracket 50. By adjusting this thread eye, the amount of looper thread taken up by the arm 45 can be varied.

When the looper 30 is retracted from the 5 needle loop and moves away from the position indicated in Fig. 2, considerable slack thread is formed between the eye of the looper and the previous interlocking of the loops, as this looper thread necessarily extends around the body of the looper moving over the edge of the fabric, and this looper must move well over the edge of the fabric in order to clear the presser foot, and stitch finger. The thread arm 45 takes up this 10 slack, drawing it back through the eye of the looper, so that when the looper 30 reaches the rear end of its stroke, its thread is substantially taut, and it is at this time that the stitch is being set. I am able, by this thread controlling device, to take practically all of the slack out of the looper thread carried by the looper underneath the work support, so that the loops in the thread 15 b may extend only across the edge of the fabric, as shown in Fig. 5. Furthermore, by this drawing of the thread back through the eye of the looper when the looper moves forward into the needle loop, there will be no thread to buckle and push the needle loop 20 aside so that the point of the looper cannot get into the same. Then again, the arm 45, when the looper is at the forward end of its stroke, is slightly below the thread guide 46, and this looper thread is taut. Upon the 25 first retracting movement of the looper 30, a little slack is given thereto which prevents chafing or breaking of the looper thread b on the looper moving over the work support. By adjusting the thread guide 46, the 30 tightness of the loops in the looper thread b may be varied.

My machine also embodies means for taking care of the slack and supplying thread to the over-edge thread carrying looper. The 35 thread c of this looper is led from the supply through a pull-off thread eye 51, and thence through a tension 52. From the tension 52 the thread passes through a thread eye 53, carried by an arm 54 adjustably attached to the standard 2 of the machine. The needle lever extension carries an arm 55, which is bent laterally and provided with a thread eye or loop 56, through which the thread c passes on its way to a fixed thread 40 guide 57 and thence to the eyes of the thread-carrying looper 38. This thread eye or loop 56 moves from a position substantially underneath the thread eye 53, to a position at the right thereof, as shown in Fig. 45 1. It, therefore, engages the looper thread and takes up the same on the retracting movement of the looper and gives free thread to the looper on its forward movement. This movement of the thread eye or 50 loop 56 causes the looper thread c to be taken

up and properly laid on the upper face of the fabric. The amount of pull exerted on this looper thread c may be varied by adjusting the bracket 54.

As the thread carried by the under thread carrying looper is the joining thread between the needle thread and the thread of the over-edge looper, the control of this thread of the under thread carrying looper will naturally affect the character of the 75 stitch. This control may be varied by the relative adjustment of the thread arm 45 and the eyelet 46. By this relative adjustment of these parts more or less of the thread of the under thread carrying looper can be put 80 into the stitch.

From the above description, it will be apparent that I have provided thread-controlling devices for each of the stitch-forming implements in a three-thread overseaming machine which may be so regulated or adjusted as to fully cover the edge of the material and form a purl along said edge of the fabric. When the parts are adjusted, as shown in the drawings, the loops in the looper thread c will be laid on the upper face of the fabric extending to the edge of the fabric. The needle loop a will pass through the fabric and will lie on the lower face of the fabric extending to the edge thereof, 95 while the loops b will extend from the upper to the lower face of the fabric only, 90 uniting the loops a and c.

It is obvious that minor changes in the details of construction and the arrangement 100 of parts may be made, without departing from the spirit of the invention, as set forth in the appended claims.

Having thus described my invention, what I claim is:

1. An over-seaming machine including in combination a thread carrying needle and complementary stitch forming mechanism, including a thread carrying looper coöperating with said needle, and devices for controlling the thread of the thread carrying looper, including an adjustable thread guide, and a thread arm coöperating therewith for taking up thread and giving up thread during the movements of the looper, 110 and means for moving said thread arm so as to take up and give up thread twice during each complete reciprocation of the looper.

2. An over-seaming machine including in combination a thread carrying needle and complementary stitch forming mechanism, including a thread carrying looper coöperating with said needle, devices coöperating with said looper and needle for forming 120 overseaming stitches, and devices for controlling the thread of the thread carrying looper, including a tension, a take-up arm between said tension and the looper, a thread guide coöperating with said arm, 125

130

and means for operating said take-up arm to take up the looper thread and pull thread through the tension from the supply, said looper thread being free from the controlling devices between said guide and the looper.

3. An over-seaming machine including in combination a thread carrying needle and complemental stitch forming mechanism, including a thread carrying looper coöperating with said needle, devices coöperating with said looper and needle for forming overseaming stitches, and devices for controlling the thread of the thread carrying looper, including a tension, a take-up arm between said tension and the looper, a thread guide coöperating with said arm, means for operating said thread arm to take up the looper thread and pull thread through the tension from the supply, and devices for supporting said thread guide whereby it may be adjusted to vary the amount of thread taken up, said looper thread being free from the controlling devices between said guide and the looper.

4. An over-seaming machine including in combination a thread carrying needle, devices for controlling said needle thread, a thread carrying looper coöperating with the needle beneath the work support, a thread carrying looper coöperating with said first named looper and with the needle above the work support, thread controlling devices for taking up and giving up thread and pulling thread from the supply for said looper coöperating with the needle above the work support, and thread controlling devices for the thread of the looper coöperating with the needle beneath the work support, said devices including a movable take-up arm for taking up and giving up thread to the looper, and for pulling thread from the supply.

5. An over-seaming machine including in combination a thread carrying needle, devices for controlling said needle thread, a thread carrying looper coöperating with the needle beneath the work support, a thread carrying looper coöperating with said first named looper and with the needle above the work support, thread controlling devices for taking up and giving up thread and pulling thread from the supply for said looper coöperating with the needle above the work support, and thread controlling devices for the thread of the looper coöperating with the needle beneath the work support, including a tension, a thread arm engaging the thread between the tension and the looper, an adjustable thread guide coöperating with said thread arm, and means for moving said thread arm for taking up the looper thread on both the forward and the rearward stroke of said looper.

6. An over-seaming machine including in combination a thread carrying needle, devices for controlling the needle thread, a thread carrying looper coöperating with the needle beneath the work support, means for moving said looper into the needle loop and for giving a dwell thereto at the forward end of its stroke, a thread carrying looper coöperating with said first named thread carrying looper and with the needle above the work support, and devices for controlling the thread of the looper coöperating with the needle beneath the work support, including a movable member, and devices for moving said member in the same timed relation as the looper beneath the work support.

7. An over-seaming machine including in combination a presser foot, a thread carrying needle, a thread carrying looper coöperating with the needle beneath the work support, a second thread carrying looper coöperating with said first named thread carrying looper and with the needle above the work support, thread controlling devices for the needle thread, including means for supplying to the needle a measured amount of thread, depending upon the thickness of the material beneath the presser foot, thread controlling devices for taking up and giving thread to the thread carrying looper beneath the work support.

8. An over-seaming machine including in combination a presser foot, a thread carrying needle, a thread carrying looper coöperating with the needle beneath the work support, a second thread carrying looper coöperating with said first named thread carrying looper and with the needle above the work support, thread controlling devices for the needle thread, including means for supplying to the needle a measured amount of thread, depending upon the thickness of the material beneath the presser foot, thread controlling devices for taking up and giving thread to the thread carrying looper beneath the work support, and thread controlling devices for taking up and giving thread to the thread carrying looper coöperating with the needle above the work support.

9. An over-seaming machine including in combination a presser foot, a thread carrying needle, a thread carrying looper coöperating with the needle beneath the work support, a second thread carrying looper coöperating with said first named thread carrying looper and with the needle above the work support, thread controlling devices for the needle thread, including means for supplying to the needle a measured amount of thread, depending upon the thickness of the material beneath the presser foot, thread controlling devices for taking up and giving thread to the thread carrying looper

beneath the work support, said thread controlling devices for the looper thread beneath the work support including an arm moving in timed relation to the looper, and taking up thread on both the forward and the rearward movements of said looper.

10. An over-seaming machine including in combination a presser foot, a thread carrying needle, a thread carrying looper co-operating with the needle beneath the work support, means for moving said looper and giving a dwell thereto at the forward end of its stroke, a thread carrying looper co-operating with the first named thread carrying looper and with the needle above the work support, and a thread controlling device for the looper beneath the work support, including a thread arm having a dwell when the looper dwells, and a thread guide
15 co-operating with the thread arm whereby said thread arm takes up and sets the stitch when the looper beneath the work support is retracted.

25 11. An over-seaming machine including
in combination a thread carrying needle, a
main pull-off for the needle thread, a ten-
sion device between the main pull-off and
the supply, and an auxiliary pull-off for the
needle thread, and devices controlled by the
30 thickness of the material for determining
the amount of thread pulled off by said
auxiliary pull-off, a thread carrying looper
cooperating with the needle beneath the
work support, means for controlling the
35 thread of said looper, and for taking up
said thread, to assist in setting the stitch,
a thread carrying looper cooperating with
said first named thread carrying looper and
with the needle above the work support.

40 12. An over-seaming machine including
in combination a thread carrying needle, a
main pull-off for the needle thread, a ten-
sion device between the main pull-off and
the supply, and an auxiliary pull-off for
the needle thread, and devices controlled
45 by the thickness of the material for deter-
mining the amount of thread pulled off by
said auxiliary pull-off, a thread carrying
loop cooperating with the needle beneath
the work support, means for controlling
50 the thread of said looper, and for taking
up said thread, to assist in setting the stitch.

a thread carrying looper coöperating with said first named thread carrying looper and with the needle above the work support, and 55 devices for taking up the thread of the looper coöperating with the needle above the work support to assist in setting the stitch.

13. An over-seaming machine including 60
in combination a thread carrying needle, a
tension for the needle thread, thread con-
trolling devices for the needle thread be-
tween the tension and the needle, a thread
carrying looper co-operating with the needle 65
beneath the work support, a tension device
for said looper thread, controlling devices
between said tension device and the looper
for taking up the looper thread, a looper co-
operating with the first named looper and 70
with the needle above the work support, a
tension device for the looper thread of said
looper co-operating with the needle above
the work support, and devices for taking
up the thread of the looper co-operating 75
with the needle above the work support.

14. A three-thread overseaming machine including in combination a needle, a constant pull-off for the needle thread, a variable pull-off for the needle thread for pulling thread according to the thickness of the material, a pull-off for one of the looper threads, a pull-off for the other looper thread, and an adjustable thread-controlling device for said last named looper thread.

15. A three-thread overseaming machine including in combination a needle, a thread-controlling device for the needle thread, a threaded looper cooperating with the needle beneath the work support, a pull-off mechanism for said looper thread, a take-up operating on said looper thread, a looper cooperating with the needle above the work support, and with said first named looper, a pull-off for said last named looper, and a take-up for said last named looper thread. 90 95

In testimony whereof, I affix my signature, in the presence of two witnesses.
